[57] CLAIM

The ornamental design for a knife sharpening hone support stand, as shown and described.

DESCRIPTION

FIG. 1 is an isometric view of a knife sharpening hone support stand, showing my new design;
FIG. 2 is a rear elevational view thereof;
FIG. 3 is a front elevational view thereof;
FIG. 4 is an end elevational view, the opposite end being a mirror image thereof;
FIG. 5 top plan view thereof; and,
FIG. 6 is a bottom plan view thereof.

*FIG. 1**FIG. 2**FIG. 3**FIG.4*

FIG.5
